UNITED STATES PATENT OFFICE

130,850

DESIGN FOR A POWDER MIXER

Adelbert C. Radtke, Oak Park, Ill., assignor to Simon S. Coates, Chicago, Ill.

Application October 12, 1940, Serial No. 95,807

Term of patent 14 years

To all whom it may concern:

Be it known that I, Adelbert C. Radtke, a citizen of the United States, residing at Oak Park, in the county of Cook and State of Illinois, have invented a new, original, and ornamental Design for a Powder Mixer, of which the following is a specification, reference being had to the accompanying drawing, forming a part thereof.

I claim:

The ornamental design for a powder mixer, substantially as shown.

ADELBERT C. RADTKE.
